UNITED STATES PATENT OFFICE.

ROLLS PERCIVAL LINK, OF LONDON, ENGLAND.

PRINTING BED FOR EMBOSSED OR IMPRINTING MACHINES.

Application filed March 17, 1926, Serial No. 95,371, and in Great Britain December 19, 1925.

This invention relates to printing beds for embossing or imprinting machines for embossing or imprinting selected designs, letters or other characters in or on suitable materials, for example, show or advertisement cards, price tickets, book covers and like articles of the kind in which the article, such as a card, ticket or the like, of sufficient thickness for the purpose, in view of the manner in which it is to be operated upon, is overlaid with a sheet of thin paper, metal or other material, with or without an adhesive coating, and hollow faced type or embossing dies are laid upon this overlay and pressed thereon to indent the paper or the like, and the card, ticket or like article, around the contour of the design, letter or other character formed on the type or die face, thereby severing from the paper or other overlaid material, the part beneath the face of the type or die and causing the severed portion to adhere to the card, ticket or other article.

The accompanying drawings show how the said invention can be conveniently and advantageously carried into practice. In these drawings:—

Figure 1 is a plan view of a combined form for holding the type or dies, and bed for the support of this form and the card or the like which is to be embossed or imprinted by the type.

Figure 2 is a front view in section on the line 2, 2, Figure 1, and

Figure 3 a side view of this combined form and bed.

Figure 4 shows a section on the line 4—4, Figure 2, and

Figure 5 shows a section on the line 5—5,

Figure 6 is a side view and

Figure 7 a plan illustrating a modified construction of the improved form and bed.

Figure 8 is a side view and

Figure 9 a plan illustrating a further modified construction hereinafter described.

Referring to Figures 1 to 5, 10 is a bed for supporting the article to be embossed or imprinted. This bed is provided with side plates 11 which, together with bars 12 extending between them across the bed, serve as a form for holding the type or dies 13. These side plates are mounted to slide vertically with respect to the upper face of the bed, on pins 14 projecting laterally from the sides of the bed through slots 15 in the said

plates. The pins also pass through slots 16 in draw bars 17 which are supported and guided between the sides of the bed and the side plates. The slots 16 are inclined, as shown, so that they act as cam faces resting on the pins 14.

By means of the draw bars and a handle 18, the bed can be moved to and fro along the lower ram plate 19 of a press. If desired, the draw bars 17 may extend downwardly below the bottom of the bed 10 and by making the bed of equal width to the lower ram plate, these draw bars may serve as lateral guides for the bed, as shown in Figure 2. When a pulling effort is exerted on the handle 18 the draw bars are moved from the position in which they are shown in Figure 3, the slots 16 sliding on the pins 14. The draw bars are thus raised and lift the side plates 11 until this movement is limited by the ends of the slots 15 coming into contact with the pins 14. Thereafter the bed is drawn along by the said bars. When a thrust is exerted on the handle 18 the draw bars are moved relatively to the bed so as to allow the side plates to descend. When the form and bed are supported on the lower ram plate of a press, the handle 18 may be acted upon to draw the bed from below the upper ram plate of the press thus simultaneously raising the bars 12 on which the type are carried away from the upper surface of the bed. On the other hand, by pushing the handle 18, the draw bars, having first allowed the side plates to descend, serve to move the bed back to a position below the upper ram plate.

The upper face of each draw bar at the part on which the corresponding side plate rests, can be inclined, the contacting face of the side plate being similarly inclined so as to increase the distance through which the side plates are lifted for a given distance moved through by the draw bars in the horizontal direction.

When the side plates are raised a sheet of suitable material, such as a card or ticket, can be withdrawn from or inserted between the faces of the type or dies and the bed without disturbing the dies or type supported on the bars 12 in their raised position.

The said transverse bars, the edges of which may be straight, curved or of other convenient shape, in addition to providing a support for the type, also act as space bars

between the lines of type. The type or dies are provided with flanges which in use rest upon shoulders 12^a formed along the sides of the bars, the bodies of the type extending downwardly between and below the lower faces of the bars with freedom to move vertically through a short distance relatively to the bars when pressure is applied to their under faces by materials resting on the bed 10 when the side plates are lowered, after which the type can be moved vertically downward, to make an impression in the said material by pressure exerted thereon, for example, by the upper ram plate of a press. The ends 15 of the bars 12 are slideable in slots formed longitudinally in the side plates, and means may be provided to hold them clamped separately in the positions to which they are adjusted to hold the type between them. As 20 clearly shown in Figure 5, the ends of these bars have slots formed therein in which an aligning bar 20 can rest. Thus when upward pressure is applied to the bars 12 (after the type therein has been moved vertically 25 upward) the bars will move upward relatively to the plate 11 and will also raise the aligning bar 20. This bar is slideable vertically on pins 21 and is pressed down by a leaf spring 22. If desired the pins 21 can 30 be replaced by clamping screws by which the bar 20 can be clamped on the said bars 12. A bed with type or dies set up between transverse bars clamped in this manner can be carried from place to place without disturbing the arrangement or setting of the 35 type or dies held therein.

In the case of type or dies movable vertically between the bars the thickness of the transverse bars at the central or thicker part 40 thereof is preferably less than the full height of the type or dies. Then, when the type or dies are resting on an article on the bed, the side plates and transverse bars being in the lower position, the backs of the type or dies project above the top faces of the bars. If the bed is now placed in a press, the upper ram plate can be caused to exert pressure 45 on the backs of the type or dies and press the faces of the type or dies into the article to a depth limited by the thickness of the bars with which the ram plate comes into contact as soon as the backs of the type or dies have been pushed down level with the tops 50 of the bars.

55 In the modified arrangement illustrated in Figures 6 and 7, side plates 23 with lower inclined edges 24 are attached to the sides of a bed 25 by screws 26 passing through slots 27 in the side plates which allow the latter to be moved vertically relatively to the bed. The bed is provided with a draw bar 28 by means of which the bed plate can be moved to and fro across the lower ram plate 30 of a press. At convenient parts of 60 the ram plate, along the sides thereof, pro-

jections 30^a are provided having inclined upper faces so that when the lower edges of the side plates are drawn over these projections the side plates are thereby raised. The side plates 23, as in Figure 1, are provided with longitudinal grooves holding 70 type supporting bars 12.

A further modification is illustrated in Figures 8 and 9. Side plates 31 are attached laterally to the bed by screws 32 passed 75 through inclined slots 33 in the plates. A spring 34 attached to the bed by a screw 35 and having its free ends respectively resting on the side plates, moves the latter so as to bring the ends of the slots 33 into contact 80 with the screws 32. A draw bar 28 is attached to the bed whereby it can be moved to and fro along a ram plate or other suitable surface having lugs 37 projecting laterally therefrom to serve as stops for the side plates 31. When the side plates have been brought into contact with the lugs the bed can be drawn between the side plates so that the screws 35 are moved along the slots 33 raising the side plates. When the bed is 85 pushed back the spring 34 moves the side plates longitudinally, so that the slots travelling across the screws cause the side plates to move downwardly.

The arrangement hereinabove described 90 forms a combined bed and form in which the type or dies when set are held in such a manner that a number of cards, tickets or other articles can be embossed or imprinted without readjustment or resetting of the type or dies. The bed and form with the type or dies set therein constitutes an independent unit which can be moved from place to place and used in any press of suitable construction. The raising or lowering 95 of the type or die carrying form from or towards the bed is effected automatically by the pull or thrust on the draw bars. Moreover, the transverse bars are so arranged that they constitute a stop limiting 100 the pressure to which the type or die faces can be subjected, so that the type or dies are protected against being damaged by excessive pressure and are prevented from penetrating too deeply into the card, ticket or 105 like article which is to be embossed or imprinted thereby.

When the handle 18 is drawn away from the side plates 11, the said side plates and type supporting bars mounted therein are 110 raised away from the bed 10 a distance which is limited by the pins 14. This allows a card or like article to be embossed to be placed upon the bed 10, the thrusting of the handle towards the side plates then causing 115 the subsequent lowering of the said side plate and type supporting bars to bring the face of type carried by the bars into contact with the article to be embossed. To prevent the exertion of pressure by the type upon 120

the article on the bed 10 during the movement of the handle towards the side walls, the type is arranged to be vertically movable relative to the type supporting bars 5 which are likewise vertically movable relative to the side walls. When the type is moved into contact with the article to be embossed, the printing bed is moved between the upper and lower ram plates of a press by 10 which pressure is exerted to force the cutting edges of the type into the article to be embossed. Subsequent to the embossing, the side walls and type supporting bars can be raised as hereinabove described to permit 15 the removal of the embossed article.

I claim:—

1. A printing bed for an embossing press having in combination therewith side plates movable vertically with respect to the bed 20 and type supporting bars movably mounted in the said side plates.
2. A printing bed for an embossing press having in combination therewith side plates movable vertically with respect to the bed, 25 type supporting bars having maximum thicknesses less than the thickness of the type, and type supporting shoulders on said bars.
3. A printing bed for an embossing press 30 having in combination therewith side plates movable vertically with respect to the bed, pins projecting from the bed through slots in the said plates, and type-supporting bars carried by said side plates.
4. A printing bed for an embossing press 35 having in combination therewith side plates movable vertically with respect to the bed, a draw bar supporting the said side plates and mounted for sliding movement relatively to 40 the said bed, and type-supporting bars carried by said side plates.

5. A printing bed for an embossing press having in combination therewith side plates movable vertically with respect to the bed, 45 and type supporting bars mounted in and movable vertically with respect to the said plates.

6. A printing bed for an embossing press having in combination therewith side plates movable vertically with respect to the bed, 50 type supporting bars carried by the said plates, and an aligning bar resting in slots in the said bars.

7. A printing bed for an embossing press having in combination therewith side plates, 55 type supporting bars carried by the said plates, an aligning bar resting in slots in the said bars, and pins carried by the side plates for guiding the said aligning bar.

8. A printing bed for an embossing press 60 having in combination therewith side plates movable vertically with respect to the bed, type supporting bars carried by the said plates, and a spring pressed aligning bar resting in slots in the said bars. 65

9. A printing bed for an embossing press having in combination therewith side plates having slots formed therein, pins projecting from the bed through the said slots, and draw bars slidably mounted between the side 70 plates and the bed and having cam faces forming the walls of slots therein through which the said pins pass.

10. A printing bed for an embossing press having in combination therewith side plates, 75 draw bars slidably mounted between the side plates and the bed, pins projecting from the bed through slots in the side plates and draw bars, and inclined contacting faces on the said plates and bars respectively.
